US0D1008227S

(12) **United States Design Patent** (10) **Patent No.:** **US D1,008,227 S**
(45) **Date of Patent:** **** Dec. 19, 2023**

(54) **WIRELESS CONTROLLER**

(71) Applicant: **Cambridge Mobile Telematics Inc.**,
Cambridge, MA (US)

(72) Inventors: **Isaku Kamada**, Cambridge, MA (US);
Melinda Liggett, Cambridge, MA (US)

(73) Assignee: **Cambridge Mobile Telematics Inc.**,
Cambridge, MA (US)

(**) Term: **15 Years**

(21) Appl. No.: **29/763,304**

(22) Filed: **Dec. 22, 2020**

(51) **LOC (14) Cl.** **14-03**

(52) **U.S. Cl.**

USPC **D14/218**

(58) **Field of Classification Search**

USPC D11/26, 29, 34, 37, 38; D14/156, 218,
D14/430, 126, 129, 132, 135, 217, 336,

(57) **CLAIM**

The ornamental design for a wireless controller, as shown and described.

DESCRIPTION

FIG. 1 is a front top perspective view of our wireless controller;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a bottom perspective view thereof.

The broken lines illustrate features of the wireless controller that form no part of the claimed design.

1 Claim, 8 Drawing Sheets
